UNITED STATES PATENT OFFICE.

PAUL KVIST, OF SEATTLE, WASHINGTON.

HAIR-CUTTING DEVICE.

Application filed October 7, 1926. Serial No. 139,994.

The object of my invention is to provide an improved device for cutting the human hair; which device is so constructed and arranged that pressure applied thereto by 5 the operator's hand will impart vibratory cutting movement to the blade element of the device.

The invention consists in the novel construction, adaptation and combination of 10 parts hereinafter described and claimed.

In the accompanying drawing,—

Figure 1 is a side elevation of a hair cutter illustrating one embodiment of my invention; Fig. 2 is a top edge view thereof; 15 and Figs. 3 and 4 are detail sectional views on lines 3—3 and 4—4 of Fig. 1. Fig. 5 is a side elevation of a hair cutter illustrating another embodiment of my invention; Fig. 6 is a top edge view thereof; Fig. 7 is 20 a view similar to Fig. 6 with the parts shown in relatively open positions; and Figs. 8, 9, and 10 are detail sectional views on lines 8—8, 9—9 and 10—10 of Fig. 5. Fig. 11 is a side elevation illustrating a 25 casing in which the cutters may be sheathed when not in use.

The cutter shown in Figs. 1 to 4 inclusive, is constructed of a thin bar of steel to provide at one end thereof a blade element 20 and at its other end a handle element 21.

The blade's upper edge 22 which constitutes the cutting edge of the device is sharpened and is inclined with respect to the longitudinal axis of the device. The cutting edge 22 extends from the outer extremity of the blade to an opening 23 which is coextensive with an arcuate slot 24 which separates the rear portion of the blade from the handle. 25 represents a slot extending length-wise of the bar below the blade and extending from in proximity of the outer end of the latter in a curve, as shown in Fig. 1, to below the bottom of the slot 24 40 into the handle 21 and thence upwardly in a curve as at 26 to the rear of the slot 24.

Extending rearwardly from the slot 26 medially of the width of the handle and to within proximity of its rear extremity is a 45 slot 27, the rear end of this slot 27 extending upwardly as at 28. As shown in Fig. 3, the slot 27 is formed to provide in transverse section a tapering upper edge 28 of the portion 21¹ of the handle below the slot 27 and a reentrant groove 29 in the lower edge of the portion 21² of the handle above

the groove. The provision of the slots 24, 25, and 26, affords curved ribs 30 and 31 which serve as springs to resiliently connect the blade 20 from its front and rear end, 60 respectively, with the front end of the handle. Moreover, the rib 31 connects the lower rear end of the blade with the upper portion 21² of the handle and the rib 30 connects the front end of the blade with 65 the lower portion 21¹ of the handle; hence, by moving the forward ends of the upper and lower portions of the handle toward and from each other, a vertical vibratory movement is transmitted through the said 70 ribs to the cutter blade.

The pressure to contract the forward end of the handle parts toward each other is accomplished by means of the operator's hand which holds the device; his other hand being employed to hold a comb, as denoted by dotted lines 33 in Fig. 1, by which the hair is brought up into cutting relation with respect to the cutting blade of the device, said 75 comb cooperating with the device by providing back support for the hair against which the blade engages in its vibratory cutting action.

The other illustrated form of the invention is shown in Figs. 6 to 10 inclusive, 80 comprises a cutting blade 35 with an inclined cutting edge 36 and having a rearwardly directed stem 37 which is mounted for movement between the lower and upper elements 38¹ and 38² of a handle.

The rear end of the blade stem is connected to one of the handle elements as by means of a resilient rib or spring 39. The rear ends of said handle elements are connected together by means of a resilient rib or spring 38³. 95 The lower handle-element 38¹ extends below the blade 35 and is formed with a groove 40 which serves as a guide way for the blade.

In proximity to the blade, the upper element 38² of the handle is bifurcated to provide a slot 41 (Fig. 6) to receive and guide the stem, and at each side of the slot, the branches at opposite sides of the stem being extended downwardly in the form of ears 42 whose lower extremities are welded to the lower element 38¹ or engaged within grooves, such as 43 provided in such handle element. The ears 42 serve as side guides for the blade and its stem, and guides supplementary thereto into the nature of lugs 44 100 are provided upon the handle near the spring 39 to obviate lateral displacement 110

of the rear end of the stem with respect to the handle. 45 represents a relatively thin extension of the blade-stem which is found to be advantageous for regulating the vibratory movement of the stem.

46 are recesses provided in each side of the respective handle elements to accommodate the thumb and a finger of the operator's hand whereby the stem is pushed in opposite lateral directions to accomplish bowing movements of the stem between the ears 42 and the lug 44 whereby the effective length of the stem is varied to impart reciprocatory movement to the blade longitudinally of the device. In use a comb as denoted by dotted lines 47 in Fig. 6 is utilized to hold the hair while being cut with shearing strokes of the blade when the latter is actuated by thumb and finger pressure applied to the stem 37 as above described. The device in either of its forms (Figs. 1 and 5) is advantageously constructed of a single piece of steel which is treated or prepared to provide sufficient resiliency to afford the vibratory movement of the blade.

In practice, the parts 30 and 31 of the Fig. 1 species and the part 39 of the Fig. 6 species constitutes springs through the action of which the vibratory movement of the respective blades are attained.

In Fig. 11 I show in elevation a casing 50 which is sewed as at 51 about its margin as by thread, and is provided in one or both sides with apertures such as 52 opening into a pocket or pockets in which one or more of the devices may be sheathed.

The construction and manner of using the invention will, it is thought, be understood from the foregoing description.

What I claim is:

1. A hair cutting device comprising a contractile handle, a blade disposed in the plane of the handle, and spring elements connecting both ends of the blade with one end of the handle.

2. A hair cutting device comprising a handle having upper and lower elements connected together at one end of the handle, a blade disposed in the plane of the handle, and spring devices connecting the opposite ends of the blade with the upper and lower elements respectively of said handle.

3. A hair cutting device consisting of a handle formed of two substantially parallel portions connected together at one end of the handle, a blade, and resilient connection between the handle and the blade, said resilient connection permitting vibratory movement of the blade with respect to the handle and in the plane of the latter.

4. A hair cutting device formed of a single piece of resilient material, comprising a cutting blade at one end and a handle at the opposite end, the handle and blade end of the device having recesses cut therein, whereby upon pressure being applied to opposite sides of the handle the blade will be vibrated.

Signed at Seattle, Washington, this 2nd day of October 1926.

PAUL KVIST.
